Primary Examiner—James R. Largen

Attorney, Agent, or Firm—Knobbe, Martens, Olson, Hubbard & Bear

[57] CLAIM

The ornamental design for a hydro-therapy fitting, as shown.

DESCRIPTION

FIG. 1 is a perspective view taken from the top, front and left side of a hydro-therapy fitting showing my new design;

FIG. 2 is a perspective view taken from the bottom rear and right side thereof; and

FIG. 3 is a cross sectional view taken on line 3—3 of FIG. 1.
